UNITED STATES PATENT OFFICE.

JACOB WHEELER, OF JOHNSONBURG, PENNSYLVANIA.

BOOKHOLDER.

Application filed August 9, 1928. Serial No. 128,901.

My present invention has reference to a case, desk or library furniture, and aims to produce a rack or holder that will accommodate any desired number of books and which 5 will hold the books in proper contacting engagement with each other to prevent displacement or accidental removal thereof.

A further object is the provision of a device for this purpose which may be employed either as a single or double holder for books, in the former instance there being arranged on a suitable base a central member or partition, while slidable on the base and movable longitudinally thereof 15 there are plates for contacting the outer books arranged on the base at the opposite sides of the partition, said movable plates being provided with a letter rack and with a card holder, while in the latter instance the 20 plate carrying the letter rack is fixed to one end of the base, the plate carrying the card compartment is movable longitudinally on the base.

To the attainment of the above broadly 25 stated objects and others which will appear as the nature of the invention is better understood, the improvement resides in certain details of construction, combination and operative association of parts, a satisfactory 30 embodiment of which is illustrated by the accompanying drawings.

In the drawings:

Figure 1 is a perspective view of the improvement.

Figure 2 is an approximately central longitudinal sectional view therethrough taken approximately on the line 2—2 of Figure 1.

Figure 3 is a transverse sectional view approximately on the line 3—3 of Figure 1.

Figure 4 is a perspective view of a second form of the improvement.

Figure 5 is a sectional view on the line 5—5 of Figure 4.

Figure 6 is a sectional view on the line 45 6—6 of Figure 5.

As disclosed by the drawings, my improvement contemplates the employment of a flat base 1, having spaced upstanding plates at and adjacent to one end thereof. 50 The outer plate is indicated by the numeral 2 and the inner plate by the numeral 3. The space between these plates provides a rack for letters or the like.

From its opposite end the base 1 is centrally channeled throughout its length, and the side walls formed by this channel are

centrally formed with tongues 4. The outer open end of the base is closed by a strip 5. Arranged for slidable movement on the base there is a plate 6. This plate is centrally 60 secured to a block 7, and the block is of a width equaling that of the opening in the base and has its sides grooved, as at 8, to receive the tongues 4 therein. The plate 6 has secured on the outer face thereof a card 65 receptacle, also fixed to and supported by the block 7.

As far as the description has progressed, it will be noted that the plate 6 will be moved longitudinally on the base toward the 70 plate 3 so that books arranged on the base will be held between the said plates 3 and 6. Preferably, however, I provide means for automatically moving the plate 6 toward the plate 3. This means simply comprises a 75 helical spring 10 that has its ends fixed to the confronting ends or faces of the blocks 7 and the plate 2, the said spring being, of course, arranged in the central opening in the base 1 and disposed below the lower edge 80 of the plate 3.

The foregoing description refers to the construction disclosed in Figures 1 to 3 of the drawings.

In Figures 4 to 6 I have illustrated a 85 second and slightly modified form of the invention. In these figures the base 11 is constructed similar to that previously described, but I let in the top of the base at the center thereof a transverse partition 90 plate 12. This plate is, of course firmly fixed to the base, while slidable on the base at the opposite sides of the partition plate 12 there are other similarly formed plates 13 and 14 respectively. The plates 13 and 95 14 have their lower edges centrally formed with extensions in the nature of depending and outwardly extending blocks 15 and 16 respectively, and the sides of these blocks are grooved to receive therein the tongues 17 on 100 the side walls provided by the central opening in the base 11. The block 16 on the plate 14 has its outer edge formed with an upstanding wall 18, and with side walls 19 which define with the wall 18 a card compartment, while the block 15 has its outer edge formed with an upstanding plate 20 that provides the upper face of the plate 13 with a letter rack. On the lower edge of the central portion of the partition or division plate 12 there is a depending element 21 to which is attached to the ends of helical 105 110

springs 22 and 23 respectively, the upper or free ends of the springs being attached to staples 24 on the inner faces of the central depending portions or blocks of the plates 5 13 and 14. The springs automatically influence the plates 13 and 14 toward the plate 12, but when the frictional engagement between the grooves and the blocks 15 and 16 and the tongues 17 is sufficient to prevent 10 free sliding of the said blocks 13 and 14, the springs 22 and 23, may if desired, be dispensed with.

The simplicity of my improvement and the advantages thereof, will, it is thought 15 be perfectly apparent to those skilled in the art to which such inventions relate when the foregoing description has been read in connection with the accompanying drawings, but I do not, of course, wish to be restricted 20 to the precise details of construction herein set forth and therefore hold myself entitled to make such changes therefrom as fairly fall within the scope of what I claim.

Having described the invention, I claim:—

A book holder comprising a flat base, having 25 a central slot therethrough, and the side walls provided thereby being formed with longitudinally extending channels, an outer and an inner plate secured to and adjacent one end of the base, the space therebetween 30 adapted for the reception of letters or the like, a strip closing the opposite and open end of the base, a vertically disposed plate arranged transversely of the base, a block to which the last mentioned plate is secured, 35 said block designed to be received in the opening of the base and having its edges grooved to receive the mentioned tongues therein, and a helical spring having one end fixed to the block and its second end fixed to the first mentioned plate and said spring being arranged in the mentioned opening in the base.

In testimony whereof I affix my signature.

JACOB WHEELER.
